CLAIM

The ornamental design for a telephone station set, substantially as shown and described.

DESCRIPTION

FIG. 1 is a front, top and right side perspective view of a telephone station set showing our new design;

FIG. 2 is a top plan view thereof;

FIG. 3 is a front elevational view thereof;

FIGS. 4 and 5 are, respectively, left and right side elevational views thereof;

FIG. 6 is a rear elevational view thereof; and

FIG. 7 is a bottom plan view thereof.

FIG. 1.

FIG. 2.

FIG. 3.

FIG. 4.

FIG. 5.

FIG. 6.

FIG. 7.
